(57) **CLAIM**

The ornamental design for an electric wine aerator and dispenser, as shown and described.

DESCRIPTION

FIG. 1 is a top view of an electric wine aerator and dispenser, showing my new design;

FIG. 2 is a bottom view thereof;

FIG. 3 is a front view thereof;

FIG. 4 is a left side view thereof;

FIG. 5 is a right side view thereof, the left side view being a mirror image;

FIG. 6 is a perspective view thereof; and,

FIG. 7 is a rear view thereof.

The broken lines in the figures illustrate portions of the electric wine aerator and dispenser that form no part of the claimed design.
